CLAIM

The ornamental design for a headset for a communication device, as shown and described.

DESCRIPTION

FIG. 1 is a front perspective view of a headset for a communication device showing my new design,

FIG. 2 is a top plan view thereof;

FIG. 3 is a bottom view thereof;

FIG. 4 is a side elevational view thereof;

FIG. 5 is an opposite side elevational view thereof;

FIG. 6 is a rear elevational view thereof; and,

FIG. 7 is a front elevational view thereof.

The broken line in FIGS. 1-7 showing environmental structures is for illustrative purposes and forms no part of the claim design.
